UNITED STATES PATENT OFFICE.

FREDERICK WATERHOUSE, OF WALLINGFORD, CONNECTICUT, ASSIGNOR
TO HALL, ELTON & CO., OF SAME PLACE.

DESIGN FOR SPOON AND FORK HANDLES.

Specification forming part of Design No. **11,508**, dated November 11, 1879; application filed October 2, 1879.
[Term of patent 3½ years.]

To all whom it may concern:

Be it known that I, F. WATERHOUSE, of Wallingford, in the county of New Haven and State of Connecticut, have invented a new Design for Spoon and Fork Handles; and I do hereby declare the following, when taken in connection with the accompanying drawing and the letters of reference marked thereon, to be a full, clear, and exact description of the same, and which said drawing constitutes part of this specification, and represents a face view.

This invention relates to a design for the handle of spoons, forks, and similar articles of table-service; and the design consists in the ornamentation of the surface of the handle, as shown in the accompanying illustration.

The outline of the handle is the same as that shown in the patent of John M. Culver, dated October 8, 1878, No. 10,859, assigned to the assignees in this application, which consists of a boss about midway of the length of the handle, and from which the handle gradually expands to near the end, thence diagonally inward to meet a semicircular tip.

In this present invention an ornamental band runs diagonally across the handle above the boss; a floriated branch springs from the boss and runs upon the surface, apparently behind the band. At the intersection of the sides with the diagonal portion a beading runs across the face from angle to angle, and on the surface in each angle below is an ornamented quadrant, with a central sprig between.

Below the tip is a beading running across from angle to angle and parallel with the beading below, the space between the two beads ornamented with light tracery.

I claim—

The ornamentation for spoon and fork handles of the shape shown, consisting of the parallel beading across the upper end from angle to angle, the ornamented quadrant in the angles below, all as shown in the accompanying illustration.

FREDK. WATERHOUSE.
